(57) **CLAIM**

The ornamental design for a light-emitting device, as shown and described.

DESCRIPTION

FIG. 1 is a top isometric view of a light-emitting device showing our new design.

FIG. 2 is a bottom isometric view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

Stippling and tangency lines shown in the drawings represent the three-dimensional contours of the design, and are not intended to indicate surface decoration. The broken lines show portions of the light-emitting device that form no part of the claimed design.
